UNITED STATES PATENT OFFICE.

JOSEPH R. HOLLAND, OF BINGHAMTON, NEW YORK, ASSIGNOR TO IRWIN M. GRAY AND GEORGE D. NASH, OF BINGHAMTON, NEW YORK, AND DANIEL S. STONE, OF SCRANTON, PENNSYLVANIA.

HORSESHOE.

SPECIFICATION forming part of Letters Patent No. 694,917, dated March 4, 1902.

Application filed June 5, 1901. Serial No. 63,182. (No model.)

To all whom it may concern:

Be it known that I, JOSEPH R. HOLLAND, a citizen of the United States, residing at Binghamton, in the county of Broome and State 5 of New York, have invented certain new and useful Improvements in Horseshoes, of which the following is a specification, reference being had therein to the accompanying drawings.

10 This invention relates to horseshoes, and has for its objects to provide a horseshoe manufactured from angle-iron, to afford a means of padding horseshoes with rubber and to improve horseshoes generally.

15 To this end the invention consists of the construction set forth herein and illustrated in the drawings, in which—

Figure 1 is an under side plan view of a horseshoe constructed according to my invention. Fig. 2 is a side elevation of one of my horseshoes attached to a hoof. Fig. 3 is a cross-section taken on the line xx of Fig. 1. Fig. 4 is a cross-section taken on the line yy of Fig. 1.

20 Similar characters of reference denote like and corresponding parts throughout the several views.

Referring to the drawings, 1 designates the plate or hoof flange, and 2 the ground or 25 flange, both being constituted from a piece of iron rolled into the form known as "angle-iron," being L-shaped in cross-section. In the construction of the angle-iron to be used in the manufacture of my shoes, at intervals 30 the flange 2 is widened or made heavier, as at 3 3, and these parts are then located so as to occupy the positions through which the nail-holes 4 4, &c., are to be made. This leaves a narrow cutting edge at 5, which serves as a 35 toe-piece, and also narrow cutting edges at 6 6 to serve the purpose of ordinary heel-calks. The thin portions of the rim 2 may be hardened, so that they will wear longer than the thicker portions 3 3. The rear portion of the 40 shoe is bent out of the plane of the front portion in the vicinity of 7 7, so that the rear portions 8 8 set downward, the lower edges thereof lining up in a plane with the tip of the toe 9 of the shoe. This arrangement affords

the equivalent of heel-calks and, besides, 50 leaves a space between the iron of the shoe and the hoof for a rubber pad 10, which pad is secured to the flange 1 of the shoe by means of rivets 11 11, passing through rivet-holes 12 12. The rivets 11 should be short enough 55 so that they are drawn down into the rubber below the level of the hoof, as illustrated in Fig. 3, and the rivets should also fit loosely in the hole 12, so that when the rubber is compressed the rivet may slide downward, as indicated by dotted lines at 13 in Fig. 3.

In constructing the iron part of my shoe an apparatus should be used to hold the front part of the shoe solid while in the heated condition, and the rear portions are then forced 65 out of the plane of the front portion, so as to take the position indicated in Fig. 2. They may be pressed out of line farther or less, according to the demands of the user, but should be forced out of line enough to accommodate 70 a rubber pad 10. The flange 2 may also be made uniform, if desired—that is, it may be uniform in thickness, if desired—so as to correspond with the thickness at the points 3 3, as shown in cross-section in Fig. 4. 75

The nail-holes 4 are approached through furrows 15 15, &c., in the flange 2, which furrows serve as a guide in directing the nail.

In using the device the rubber pads are riveted to the iron part before attaching to the 80 hoof. The shoe is then attached by means of nails in the ordinary way.

Having thus described my invention, what I claim, and desire to secure by Letters Patent, is— 85

1. The herein-described horseshoe comprising a front semicircular part provided with the usual nail-holes, a rear part consisting of the heel portions bent out of the plane of the rest of the shoe and adapted to receive a soft- 90 tread substance between the hoof and the shoe, the said substance being held to the body of the shoe by sliding rivets arranged to slide downward through a flange of the shoe upon compression of the soft tread, substan- 95 tially as and for the purpose specified.

2. As a new article of manufacture, a horseshoe constructed from angle-iron L-shaped in

cross-section, and comprising a front portion adapted to lie flat against the hoof, and provided with the usual nail-holes for the purpose of nailing the same thereto, and a rear part consisting of the heel portions bent out of the plane of the rest of the shoe and adapted to receive a soft-tread substance between the hoof and the shoe, the said substance being held to the body of the shoe by sliding 10 rivets arranged to slide downward through a

flange of the shoe upon compression of the soft tread, substantially as and for the purpose specified.

In testimony whereof I affix my signature in presence of two witnesses.

JOSEPH R. HOLLAND.
